United States Patent Office

Des. 183,518
Patented Sept. 16, 1958

183,518

BUTTER DISH

Edward E. Heck, Berwyn, Ill., assignor to Republic Molding Corporation, Chicago, Ill., a corporation of Illinois

Application July 6, 1955, Serial No. 36,831

Term of patent 14 years

(Cl. D44—5)

Fig. 2.

Fig. 3.

Figure 1 is a perspective view of a butter dish embodying the design;

Fig. 2 is a side elevational view of the same; and
Fig. 3 is an end elevational view of the same.

I claim:

The ornamental design for a butter dish, substantially as shown.
